UNITED STATES PATENT OFFICE.

BELLE McCORD ROBERTS, OF LONG BEACH, CALIFORNIA.

POWDER BOX.

Application filed May 18, 1927. Serial No. 192,255.

This invention relates to powder-boxes, and in particular, to a vanity device wherein there is a receptacle having a powder applicator permanently mounted therein, and wherein there is a mirror associated with said receptacle that will enable a person to effectively apply powder to the skin.

A further object of this invention is to provide a powder applicator in which powder is adapted to be stored, and which provides means whereby, when the supply of powder is exhausted, the applicator may be refilled.

These objects have been accomplished by means of such structure and relative arrangement of parts as will fully appear by a perusal of the following specification and claims.

With the foregoing and other objects in view which will be made manifest in the following detailed description and specifically pointed out in the appended claims, reference is had to the accompanying drawings for an illustrative embodiment of the invention, wherein:

Figure 1 is a side view of my improved powder-box.

Fig. 2 is a plan view of the box cover.

Fig. 3 is a plan view of the box with the cover removed to more clearly illustrate the nature of my invention.

Fig. 4 is a sectional view taken substantially along the lines 4—4 of Figure 1.

The device involves in its general organization a receptacle 1, having a cover 2 removably mounted upon the same. This cover has provided on the annular wall thereof, a plurality of inclined, pressed beads providing grooves 4 on the inner side of the cover. A plurality of small projections 6 formed on the outer side of the annular wall of the receptacle, are receivable in these grooves, so that when the cover is inserted over the receptacle, a quarter of a revolution or less of the cover will serve to lock the same firmly in place. A flexible puff is mounted in the receptacle. This puff is designated at 5 and has an outer applying surface 7. A narrow slit is formed in this applying surface, which slit is designated at 10, and inwardly extending flaps 11 provide a filling valve for powder stored within the puff. The puff has a bottom 12, and this bot-

tom is extended to provide a marginal, flexible flap 13. A resilient, metallic ring having an outside diameter substantially equal to the inside diameter of the receptacle, is mounted within the same and firmly holds the flap 13 against the annular wall of the receptacle. This metallic, ring-like member is designated at 20, and is split as at 21 to provide inwardly extending finger-grips 22. This ring-like member is formed of resilient material and normally tends to extend its diameter so that the pressure upon the finger-grips will release the flap 13 from its binding engagement with its ring-like member, and the puff may be removed from the container. A mirror is mounted in the cover 2 and is designated at 23. This mirror is firmly held in place by means of a bezel 24.

In actual operation the device may be filled through the filling valve, and when filled, the action of this valve prevents powder from leaking out of the puff. The puff is made of porous material, and tapping the same upon the skin will cause a sufficient quantity of powder to pass through to the applying surface. With the aid of the mirror in the cover, the user may effectively apply the powder where desired without removing the puff from the receptacle.

It will be understood that various changes in details of construction may be made without departing from the spirit or scope of the invention as defined by the appended claims.

I claim:

1. A powder-box comprising a receptacle, a puff having a marginal flap mounted in said receptacle, and means engaging said flap for holding said puff in said receptacle.
2. A device as claimed in claim 1, said means comprising a split ring adapted to bear against said flap and hold the same against the wall of said receptacle.
3. A device of the character described comprising a receptacle, a puff mounted in said receptacle, said puff having a bottom and an applying surface, said bottom being extended beyond said applying surface to provide an annular flap, a split ring having inwardly extending finger-grips mounted in said receptacle, said ring bearing against said flap and pressing the same against the wall of said receptacle, a slit in said puff, in-

wardly extending flaps adjacent said slit, providing a filling valve and a cover for said receptacle.

4. A device as claimed in claim 3, said cover having a mirror therein and a bezel holding said mirror in place.

5. A device of the character described comprising a receptacle, a puff adapted to

be filled with powder and comprising a porous applying surface and a flap, and a resilient ring adapted to engage said flap to retain the puff within the receptacle. 10

In testimony whereof I have signed my name to this specification.

BELLE McCORD ROBERTS.
